SWITCH

**Lionel P. Hopkins, Summit, N. J., assignor to the
United States of America as represented by the
Secretary of the Army**

Application June 16, 1952, Serial No. 293,753

3 Claims. (Cl. 200—8)

1

The present invention relates to electric switches.

The primary object of the invention is to provide a switch of the multi-circuit variety which is of small size and still controls a large number of circuits.

Another object of the invention is to provide a switch having a multiplicity of electrical contacts within a housing and a revolvable contactor shiftable for establishing electrical connection therewith.

Another object of the invention is to provide a switch wherein all the movable contacts are contained within the housing whereby such contacts will be made sparkproof, dustproof, etc., when such features are desired or necessary.

Other objects and features of the invention will be apparent from the following description to be read in view of the accompanying drawing in which:

Fig. 1 is a cut-away view in perspective of a preferred form of switch embodying the invention;

Fig. 2 is a section taken on the line 2—2 of Fig. 1, looking in the direction of the arrows, and

Fig. 3 is a section taken on the line 3—3 of Fig. 1, looking in the direction of the arrows.

Referring particularly to the drawing, the switch comprises basically an elongated cylindrical casing 11 having a cover 13 at one end thereof. The cover 13 has an opening to accommodate a rotatable shaft 15, a portion of which extends exteriorly beyond the case 11 and cover 13 and the remainder extends into the casing 11. For supporting the shaft 15, there is provided a bearing which is not described in detail as such bearing is conventional and forms no part of the invention. For effecting rotation of the shaft 15, a knob (not shown) can be secured to the exposed portion of the shaft by any conventional means, such as a set screw. Such knob can be either manually controlled or motor driven. The other end of the shaft 15 terminates in an enlarged rotor portion 17, which, while shown as hexagonal in shape, may be of any desired geometric configuration and has a series of notches as shown, which rotor portion is revolvable with the shaft 15.

Secured about the periphery of the rotor portion 17 and equally spaced from each other are three substantially U-shaped contactor members designated generally as 19. In the specific embodiment shown herein, each rotatable contactor member 19 comprises mutually spaced spring-like leaf members 21, 23 wherein one end of each of

2

said members 21, 23 terminates in a common base portion, which is affixed to the rotor portion 17. The free ends of the said leaf members 21, 23 terminate in flattened contacts 24 and 26, respectively. The contacts 24 and 26 are adapted to physically and separately engage one of a plurality of terminals 25 as hereinafter set forth. In the embodiment shown herein, three such contactor members are shown which are arcuately positioned about rotor portion 17, and of such length that the three contactors substantially engirdle the rotor.

The terminals 25 are longitudinally disposed within the casing and about a core 27, made of an insulating material, which has an outside diameter substantially equal to the inside diameter of the casing 11. The terminals 25 lie in longitudinal grooves formed in the core 27. The core 27 can be secured to the case 11 by any conventional means such as by bolts (not shown), thus holding the terminals securely in position within the casing. Each of the terminals 25 extends beyond the casing 11 for connection to any desired electric circuitry. Within the casing three of the terminals 25 are provided with right angle arcuate terminal extensions 29. As is evident from the drawing, it can be seen that the contact portion 24 of leaf member 21 of the contactor member 19 is in rotatable slidable engagement with extension 29, while the contact portion 26 of leaf member 23 is in rotatable slidable engagement with the ends of the remaining terminals 25, that is, all the terminals not having extensions 29 as heretofore described. Each of the extensions 29 has a radially extended lug 31 which is rigidly fixed into an opening 33 in the casing 11 for maintaining the extension 29 in place.

In operation, the shaft 15 is rotated thereby effecting movement of the contactor members 19. In the course of such movement or rotation, the contact 24 of each contactor member 19 will electrically engage one of the extensions 29, while the contact one of 26 will electrically contact the remaining terminals. Thus, in step-by-step progression, a multiplicity of electrical connections can be accomplished.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. A switch comprising a casing, a rotatable shaft longitudinally positioned within said casing,

a plurality of bar terminals that define a circle coaxial with said shaft and disposed within said casing, a plurality of said terminals extending beyond the common ends of the remainder of said terminals, each of said extending terminals terminating in an arcuately shaped portion which together substantially engird said rotatable shaft, a plurality of contactors secured about said rotatable shaft, each of said contactors comprising two spaced contact elements, whereby when said shaft is rotated one of said contact elements of each of said contactors engages one of said arcuately shaped portion while the other of said contact elements engages at least one of said remaining terminals.

2. A switch comprising a casing, a rotatable shaft longitudinally positioned within said casing, a plurality of terminals longitudinally disposed within said casing that define a circle that is concentric with and spaced from said shaft, at least one of said terminals extending beyond the ends common to the remainder of said terminals and provided with an arcuately shaped contact portion which extends beyond the end of at least an adjacent terminal in the arcuate direction, a plurality of contactors secured about said shaft, each of said contactors comprising a substantially U-shaped member having two mutually spaced spring leaf members, whereby as said shaft

is rotated the free end of one of said leaf members contacts said extended terminal and the other of said leaf members contacts at least one of said remaining terminals.

- 5 3. A switch comprising a casing, a rotatable shaft longitudinally positioned within said casing, a plurality of terminals longitudinally disposed within said casing that define a circle that is concentric with and spaced from said shaft, a plurality of said terminals extending beyond the ends common to the remainder of said terminals, each of said extended terminals provided with a right angle arcuate shaped extension contact portion, which together substantially engird said rotatable shaft, a plurality of contactors secured about said shaft, each of said contactors comprising a substantially U-shaped member having two mutually spaced spring leaf members, whereby as said shaft is rotated the free end of one of said leaf members contacts one of said extended terminals and the other of said leaf members contacts at least one of said remaining terminals.
